ALBERT D. TRENOR, OF NEW YORK, N. Y., ASSIGNOR TO JOHN HAYS HAMMOND, JR., OF GLOUCESTER, MASSACHUSETTS.

MEANS FOR DIVERTING A DIRIGIBLE BODY FROM A PREDETERMINED STRAIGHT COURSE TO A PREDETERMINED STRAIGHT COURSE PARALLEL TO ITS ORIGINAL COURSE.

Application filed April 15, 1920, Serial No. 374,206. Renewed April 27, 1923.

To all whom it may concern:

Be it known that I, ALBERT D. TRENOR, a citizen of the United States, and a resident of the city of New York, in the county and State of New York, have invented certain new and useful improvements in means for diverting a dirigible body from a predetermined straight course to a predetermined straight course parallel to its original course, of which the following is a specification.

Some of the objects of this invention are to provide means whereby a torpedo or other dirigible body may be caused to deviate from its course, and, after following a predetermined curve, be directed on a course which will be parallel to its original course but displaced from it selectively either to the right or to the left by a predetermined distance; and to provide other improvements as will appear hereinafter.

In the accompanying drawings, Figure 1 is a diagrammatic representation of one course which the movable body may be caused to follow while under the control of means constructed in accordance with this invention; Fig. 2 a side elevation of one form of mechanism constructed in accordance with this invention and installed in a torpedo; Fig. 3 a fragmentary plan view of a part of this mechanism; Fig. 4 a sectional elevation on line 4—4 of Fig. 3, some parts being omitted for clearness; Fig. 5 a transverse section on line 5—5 of Fig. 2; Fig. 6 a fragmentary end elevation of part of the mechanism shown in Fig. 2; Figs. 7, 8 and 9 depict in three different positions respectively a rotary valve forming part of this invention; Fig. 10 is a sectional view showing an auxiliary mechanism constructed in accordance with this invention which may be added to that shown in Fig. 2 for causing the dirigible body to follow a different curve from that shown in Fig. 1; and Fig. 11 is a diagrammatic view of a course which a dirigible body may be caused to follow when the mechanism shown in Fig. 10 is operating in connection with that shown in Fig. 2.

The form of this invention shown in Figs. 2 to 9 inclusive is provided to steer a torpedo or other dirigible body on a predetermined

varying course such for instance as is shown by the full line in Fig. 1, in which the body first proceeds under the control of a gyroscope in the direction of the arrow upon an approximately straight course 15. At a point 16, in response to an impulse of radiant energy, the gyro control is disconnected and the rudders of the torpedo are turned hard to port. The torpedo immediately starts turning on a curve 17, which approaches the arc of a circle but which, due to the inertia of the torpedo, deviates slightly therefrom. After the torpedo has reached a point 20, which is substantially at a predetermined distance 21 from the point 16 measured on the curve 17, the gyro control is automatically thrown in and the torpedo starts on a reverse curve 22 similar to 17. This eventually brings the torpedo back upon a course 24 which is parallel to the course 15 and displaced from it by substantially a predetermined distance 25. As the curve 17 is a definite curve for a certain speed of torpedo and a certain throw of the rudder, the distance 25, which separates the old from the new course, will be dependent upon the distance 21 and therefore by regulating the distance 21 any desired displacement 25 can be obtained.

In Figs. 2 to 9, one form of this invention is shown as arranged in the hull of 30 of a torpedo provided with two propellers 31 and 32, mounted respectively upon two tubular coaxial propeller shafts 33 and 34. The torpedo is also provided with two vertical rudders 35 and 36 for controlling the motion of the torpedo in a horizontal plane. The rudders 34 and 35 are rigidly secured to a rudder post 37, which passes through the hull of the torpedo and is curved around the propeller shafts 33 and 34.

For controlling the vertical rudders 35, 36, an arm 38 is rigidly secured to the rudder post 37. To the outer end of this arm 38 is connected a link 39, the other end of which is connected to a steering piston rod 41, which is rigidly secured to a piston 42 which reciprocates in a cylinder 43 and which is controlled by a valve 45. This valve is provided with two annular grooves 46 and 47. A pipe 48, which supplies compressed air, is controlled by the valve 45. A valve

stem 49 secured to the valve 45 is prolonged and is arranged to reciprocate through a fixed bearing 50.

For automatically controlling the vertical 5 rudders 35 and 36 the valve stem 49 is provided with a pin 52 fixed thereon which engages a slot 53 in an arm 54. This arm 54 is rigidly secured to a shaft 56 arranged to oscillate in fixed bearings in a fixed bracket 10 57. The part of this shaft 56 below the bracket 57 is square-shaped in transverse section. Surrounding this square part and held against rotation with respect thereto is a member 60, which is arranged to reciprocate 15 longitudinally of the square part of the shaft 56, the member 60 being provided with a central squared aperture in which the squared portion of the shaft 56 fits snugly but leaving the member 60 free to slide longitudinally of the shaft 56. The upper part 20 of the member 60 is provided with an annular groove 61 in which engages two diametrically opposed ends of a yoke 62. Integral with the lower part of this member 25 60 is an L-shaped member 64. One arm of this member 64 is connected to one end of a link 66, the other end of which is connected to one arm of a similar L-shaped member 67. The member 67 is provided with an annular groove 68, in which engages two diametrically opposed ends of a yoke 69. This 30 yoke 69 is rigidly connected to the yoke 62 by means of a member 70 which is terminally pivoted to two fixed brackets 71 and 35 72. The member 67 is rotatable and longitudinally slideable on a fixed cylindrical shaft 73 which is supported by a fixed bracket 74. The members 64 and 67 are arranged to be actuated by a palette member 40 75. This member 75 is carried by a member 76 but is free to oscillate with respect to said member 76 about an axis fixed with respect to the member 76 and extending diametrically thereof. The member 76 is arranged 45 to reciprocate in fixed bearings 78, 79. The lower end of the palette member 75 is provided with two lugs 80 and 81 at different elevations. The lug 80 cooperates with a disk 82 and the lug 81 cooperates with a 50 disk 83. These disks are rigidly secured to a vertical gimbal ring 85 of a gyroscope 86. The gyro mechanism is supported in fixed bearings 88, 89 in a fixed casing 90. The yoke 62 is rigid with and forms part of a 55 member 92, which is pivotally connected by a link 93 to a bell crank 94 which is pivoted to a fixed bracket 95. A spring 96 normally holds the members 92 and 94 yieldingly in the position shown in Fig. 2. A vertical 60 member 100 reciprocates in fixed bearings 101, 102 and carries a pin 103 rigid therewith, which is arranged to actuate alternately the two members 92 and 94. The member 100 is provided with an opening 65 105 and the valve stem 49 carries a pin 106

rigid therewith which projects into this opening. The lower end of the member 100 carries a pin 107 rigid therewith which engages in a slot 108 provided in one arm of a bell crank lever 109 which is pivoted at 70 110 to oscillate about fixed axis. The other arm of the lever 109 is provided with a slot 111 which engages a pin 112 fixed on a piston rod 115 to which is secured a piston 116, which reciprocates in a cylinder 117. 75

For automatically throwing the gyro 86 into control of the vertical rudders 35 and 36 a predetermined time after it has been disconnected in response to a radio signal for selective steering, a cam-shaped member 80 118 is secured to the piston rod 115 and the whole is normally held in a central position by means of springs 119, 120. A bracket 121 is provided, in which the rod 115 has a sliding bearing. A lever 125 is pivoted at 126 to a fixed support 127 and one end of the lever 125 is yieldingly held in engagement with the cam 118 by means of a spring 128. The other end of the lever 125 is provided with a yoke 128' which cooperates with a grooved member 129 which is rigidly secured to one end of a shaft 130. This shaft 130 is free to rotate and to reciprocate in the support 127 and carries at its other end an idler friction cone 131 rigidly secured thereto. This cone 131 is arranged to be reciprocated into and out of engagement with two main friction cones 132 and 133. One of these main cones 132 is rigidly secured to a shaft 134 rotatably supported at 100 one end by the support 127 and at its other end by a fixed bearing 135 and is provided with a worm wheel 136 rigid therewith which is driven by the worm 137. The worm 137 is mounted on a shaft 138 which is rotatably supported in fixed bearings 139, 140, 141 and to which is rigidly secured a gear 145. This gear meshes with an idler gear 146 which is rotatably supported by the bearings 140, 141 and meshes with a gear 147 which is rigidly secured to the outer propeller shaft 34. To the outer end of the shaft 138 is rigidly secured a bevel gear 148 which meshes with and drives a bevel gear 148'. The bevel gear 148' is rigidly secured to an eccentric 149 which is rigid with a shaft 149' rotatably supported in the bracket 139. The eccentric 149 rotates in the slotted end of the member 76 and when it is rotated causes this member to reciprocate in the bearings 78 and 79, thus reciprocating the palette member 75 with it. The lugs 80 and 81 of this member 75 cooperate with the disks 82 and 83, and the top part of the member 75 cooperates with the members 64 and 67 alternately. The friction cone 133 is rigidly secured to an oscillatory shaft 150 which is provided with a lug 151 rigid therewith and normally held against a pin 152 by means of a coiled 115 120 125 130

spring 153. The outer end of the shaft 150 carries a cam 155 which is rotatively adjustable with respect to the shaft 150 and which may be clamped in any position of adjustment on the shaft 150 by means of a nut 156. The cam 155 actuates a reciprocating valve 158 which reciprocates in a fixed valve casing 159. The valve 158 is provided with an annular groove 160, and a coiled spring 161 holds the valve 158 yielding against the cam 155. An exhaust port 161' is provided in the top of the valve casing 159. The valve casing 159 is connected to a supply of compressed air by means of a pipe 162, and the valve casing 159 is connected by a pipe 163 to a fixed cylinder 164 in which reciprocates a piston 165 normally held at the right-hand end of the cylinder by a spring 166. A valve 167 rigid with the piston 165 is provided for controlling the admission and exhaust of the air from a fixed cylinder 168. The valve 167 is provided with two annular grooves 172 and 173, and is normally held in the position shown in Fig. 2 by the spring 166. A piston 174 reciprocates in the cylinder 168 and is secured to a piston rod 175, and is held at the left-hand end of the cylinder by a spring 175'. The outer end of the rod 175 is cut in the form of a rack which meshes with a gear 176 which is rigidly secured to a plate 177, and the gear 176 and plate 177 are loosely mounted on a shaft 177'. A spring pressed pawl 178 is pivotally secured to the plate 177 and engages a four-tooth ratchet 179 rigid with the shaft 177'. The shaft 177' is rigid and coaxial with a rotary valve member 180 which rotates in a fixed valve casing 181 and is provided with two transverse apertures 182 and 183, the former of which extends entirely through the valve and the latter of which extends half way through the valve. A longitudinal aperture 184 extending axially part way through the valve forms an exhaust from the apertures 182 and 183. The apertures 182 and 183 at suitable times, depending upon the position of the valve 180, cooperate with two pipes 188 and 189 which are connected to and communicate with opposite ends of the cylinder 117. An annular groove 190 is provided in the rotary valve 180 and communicates with a longitudinal groove 191 provided in the valve, which at suitable times connects either the pipe 188 or 189 to a supply pipe 192 communicating with the source of compressed air.

For selectively steering the torpedo either to the port or to the starboard, at the will of the operator, subject to the limitations hereinbefore described, the left-hand end of the valve 167 forms the core of a solenoid 195, the opposite ends of the winding of which are connected respectively by wires 196 and 197 to any suitable wireless receiv-

ing apparatus 198. The latter is connected to and receives energy from an antenna 199 which trails behind the torpedo during its run, and which is arranged to respond to electroradiant impulses.

70

In the operation of the form of this invention shown in Figs. 1 to 9 inclusive of the drawings, the torpedo normally proceeds on an approximately straight course under the control of the gyroscope 86 which acts through the palette member 75 which is continuously and rapidly reciprocated by means of the member 76 driven by the eccentric 149. The eccentric 149 is continuously rotated by the bevel gears 148 and 148' and the gear train 145, 146 and 147 from the propeller shaft 34 of the torpedo.

75

If while under the control of the gyroscope 86, the torpedo should be diverted to the right from the substantially straight course determined by the gyroscope, the lug 80 of the palette member 75 will strike the edge of the disk 82, thus rotating the palette member 75 through a small angle in a clockwise direction as seen in Figs. 3 and 5. The palette member 75 will thus be caused to engage the member 64 and rotate it in a clockwise direction, thus rotating the arm 54 in the same direction. This moves the valve stem 49 to the right, as seen in Fig. 2, thus allowing air to flow from the pipe 48 through the annular groove 47 into the left-hand side of the cylinder 43, thus forcing the piston 42 to the right, which turns the rudders 35, 36 to the left, thus returning the torpedo to its course.

80

If, while under the control of the gyroscope 86, the torpedo should be diverted to the left, the lug 81 would strike the edge of the disk 83, rotating the palette member 75 through a small angle counter-clockwise. The palette member will thus be caused to engage the member 67 and rotate it in a counter-clockwise direction, which by means of the link 66 would rotate the member 64 counter-clockwise, as seen in Fig. 3. This would rotate the arm 54 counter-clockwise, thus moving the valve stem 49 to the left, as seen in Fig. 2, thus allowing compressed air to enter the right-hand end of the cylinder 43 to turn the rudders to the right thus returning the torpedo to its course.

95

When it is now desired to have the torpedo follow the curved course 17, shown in Fig. 1, an impulse of electroradiant is sent from the distant control station, and is received on the antenna 199. This causes the wireless receiving apparatus 198 to function, thus energizing the solenoid 195 which pulls the valve 167 to the left, thus allowing compressed air to enter from the pipe 169 through the annular groove 172 into the cylinder 168, thus moving the piston 174 to the right, which by means of the rack on the piston rod 175 rotates the gear 176 which

100

105

110

115

120

125

130

rotates the plate 177 and the spring pressed pawl 178, which by means of the ratchet 179 turns the rotary valve 180 through a quarter of a revolution into the position shown in Fig. 7. At the end of this impulse of electro-radiant energy, the solenoid 195 is deenergized and the valve 167 is returned to its initial position under the action of the spring 166. This allows the air in the cylinder 168 to exhaust through the groove 173, and the piston 174, rack 175, gear 176, plate 177 and pawl 178 are returned by spring 175' to their initial positions leaving the rotary valve 180 in the position shown in Fig. 7. 10 This allows air to enter from the pipe 192, and pass along the groove 191 into the pipe 189, and thus into the right-hand end of the cylinder 117, thus forcing the piston 116 to the left. This, through the bell crank lever 109, causes the member 100 to be moved down. The pin 103, engaging the bell crank 94, rotates it in a clockwise direction, which by means of the link 93 rotates the member 92 and its yoke 62 in a clockwise direction. 15 This yoke 62 being rigidly connected to the yoke 69 causes both members 60 and 67 to move down. Thus the arms 64 and 67 of these members move into inoperative positions with respect to the palette member 75 20 and are therefore not influenced by the gyroscope. As the member 100 moves down, the walls of the slot 105 cooperate with the pin 106 to cause the valve stem 49 to move to the right, thus turning the vertical rudders, as previously described, to the left. This causes the torpedo to run on the course 17. When the piston rod 115 was moved to the left, the cam-shaped member 118 moves from under the member 125, thus allowing it to be 25 rotated in a clockwise direction by means of the spring 128, which forces the idler friction cone 131 simultaneously into engagement with the friction cones 132 and 133, the cone 132 being driven at a fixed rate of speed from the propeller shaft 34 by means of the gears 147, 146 and 145 and the worm and wheel 137 and 136. This causes the shaft 150 to be rotated at a speed which is proportional to the distance covered by the 30 torpedo, the cam 155 being so set that when the torpedo has travelled a predetermined distance 21 on the curve 17, the cam 155 will raise the valve 158, thus allowing air to pass from the supply pipe 162 through the annular groove 160, through the pipe 163 into the cylinder 164, thus moving the valve stem 167 to the left, which rotates the rotary valve 180, as previously described, through one-quarter of a revolution into the position 35 shown in Fig. 8. In this position, the pipes 188 and 189 are connected to the exhaust 184 and the piston rod 115 is returned to a central position under the action of the springs 119 and 120, the member 125 riding up on the cam 118, thus moving the cone 131

out of engagement with the cones 132 and 133. The shaft 150 will therefore be returned to its initial position under the action of the coiled spring 153, the cam 155 and the valve stem 158 returning to their initial 70 position. The air in the cylinder 164 now exhausts from the pipe 163 and port 161' and the valve stem 170 returns to its initial position under the action of the spring 166. This allows the air to exhaust from the cylinder 168 and the piston 174, rack 175, gear 176, plate 177 and pawl 178, are returned to their initial positions under the action of the spring 175' leaving the rotary valve 180 in the position shown in Fig. 8. The position of the cam 155 with respect to the shaft 150 is figured out beforehand and is set by means of the nut 156, so that the torpedo covers a distance 21 on the line 17 before the valve 158 is operated, and by varying this adjustment the distance 21 can be varied and therefore the displacement 25 can be varied. The returning of the piston rod 115 to its initial position also returns the member 100 to its initial position, thus returning the pin 103 to a central position, and the members 94 and 92 will be returned to their initial position under the action of the spring 96. This causes the yokes 62 and 69 to be raised, thus bringing the members 64 and 67 back into operative positions and therefore bringing the torpedo under the control of the gyroscope. The torpedo will then start to return to a course 24 parallel to its initial course under the action of the gyroscope, 100 as described in the first part of the description of the operation. This course 24 is displaced a distance 25 from the initial course 15, which is the desired distance. The rotary valve 180 is now in a neutral position 105 (Fig. 8) and the torpedo continues upon the course 24 under the action of the gyroscope. If it should be desired to displace the torpedo a distance 25 to the right, thus bringing it back to its original course, an 110 impulse of electroradiant energy is sent when the torpedo is at any position 210. This impulse turns the rotary valve 180 into the position shown in Fig. 9, thus allowing air to enter the pipe 188, moving the piston rod 115 to the right and the member 100 upward, and the pin 106 engaging with the member 92 depresses the yokes 62 and 69, thus disconnecting the gyro control, as previously 120 described. The opening 105 will then operate with the pin 106 to cause the valve stem 49 to move to the left, thus allowing air to enter the right-hand end of the cylinder 43, which will turn the rudders 35 and 36 to the right on the course 211. The member 125, moving over the cam 118, throws the cone 131 into engagement with the cones 132 and 133, thus starting the rotation of the cam 155. After the torpedo has travelled 125 over the course 211 through a distance 212 130

which is equal to the distance 21, the cam 155 operates the valve 158 to turn the rotary valve 180 into the position shown in Fig. 2. This returns the torpedo to gyro control, as 5 previously described, and causes it to move over the curve 213 and return on the original course 15. By sending a suitable number of impulses, the torpedo may be caused to be displaced step by step any given amount 10 either to the right or to the left as may be desired.

In the modified form of this invention shown in Fig. 10, the construction is the same in every detail as that hereinbefore 15 described except that to retard the action of the steering mechanism when it is being selectively controlled independently of the gyroscope and in response to an impulse of electroradiant energy, a fixed cylinder 225 20 is provided between the hereinbefore described cylinder 43 and the hereinbefore described link 39. This cylinder is provided with a piston 226 and pipes 227 and 228 communicating therewith. These pipes are 25 connected to a fixed valve casing 229, provided with a valve 230. The valve 230 is provided with two ports 233 and 234, the former being the full size of the pipes 227 and 228, the latter being a relatively very 30 small opening of suitable size. The valve 230 is pivotally connected to a yoke 235 which is normally held against stops 236 by means of a spring 237. The two ends of 35 the yoke 235 are connected to piston rods 240 and 241, which are connected to pistons 242 and 243 reciprocating in cylinders 244 and 245. These cylinders are connected by pipes 247 and 248 to the pipes 188 and 189. The object of this modified form is to cause 40 the torpedo to move over a course in the form of a compound curve made up of curved portions approximating portions of a spiral.

In the operation of the modified form 45 of this invention shown in Fig. 10, the torpedo normally proceeds, as shown in Fig. 11, upon a substantially straight course 251 under control of the gyroscope 86. When so proceeding, assuming that the valve 180 50 should be positioned as shown in Fig. 2, if an impulse of electroradiant energy should be transmitted from the control station when the torpedo happened to be at a point 253 of its course, the gyroscope would be 55 rendered inoperative to control the torpedo and the torpedo would be steered towards the left in response to the signal. During 60 this operation the compressed air entering the pipe 189 passes into the pipe 248, thus moving the piston 243 upward, which causes the yoke 235 to rotate about its opposite end, thus forcing the valve 230 upward and bringing the port 234 into alignment with the pipes 227 and 228. The cylinder 225, being filled with oil, glycerine 65

or other suitable fluid, acts as a dash pot and causes the rudders 34 and 35 to be gradually thrown over and not suddenly, as is shown in Fig. 2. This causes the torpedo to follow along a curved path 252 approximately a portion of a spiral (see Fig. 11). After the torpedo has traversed a predetermined distance 254, the cam 155 operates to turn the rotary valve 180 into the 70 position shown in Fig. 8, thus throwing the 75 torpedo under the control of the gyroscope 86 and exhausting the air from the cylinder 245. The valve 230 then returns into its initial position as shown in Fig. 10 under 80 the action of the spring 237 and the torpedo is returned to a course 255 parallel to its original course 251 but displaced from it a distance 256, which can be calculated from the distance 254 and the speed with 85 which the rudders 34 and 35 are turning.

If when the torpedo is proceeding upon a substantially straight course under control of the gyroscope 86, and the valve 180 instead of being set as shown in Fig. 2 90 happens to be set in a position reached by rotating the valve through 180 degrees from the position shown in Fig. 2, then upon receipt of a suitable signal of electroradiant energy by the antenna the gyro would be rendered 95 inoperative to control the torpedo and the torpedo would be steered to the right as a result of the signal and would follow a curved path to the right until the torpedo is automatically placed again under control 100 of the gyro and caused to proceed upon a substantially straight course parallel to its original course and spaced therefrom to the right a predetermined distance as hereinbefore described.

Having thus described this invention, I 105 claim:

1. The combination with a dirigible body, of means carried thereby for propelling the same, stabilizing means carried by said body and automatically operative to stabilize 110 said body about a predetermined axis, means responsive to radiant energy for controlling the potentiality of said stabilizing means to stabilize said body, and means controlled by said propelling means for automatically controlling the potentiality of 115 said stabilizing means.

2. The combination with a dirigible body, of means carried thereby for propelling the same, stabilizing means carried by said body and automatically operative to stabilize said body about a predetermined axis, means responsive to radiant energy for varying the potentiality of said stabilizing means to stabilize said body, and means controlled by 120 said propelling means for automatically varying the potentiality of said stabilizing means to control said body.

3. The combination with a dirigible body, of means carried thereby for propelling the 130

same, stabilizing means carried by said body and automatically operative to stabilize said body about a predetermined axis, means responsive to radiant energy for rendering said stabilizing means inoperative to stabilize said body, and means controlled by said propelling means to render said stabilizing means operative to control said body after said stabilizing means, in response to radiant energy, has been rendered inoperative to control said body.

4. The combination with a dirigible body, of means carried thereby for stabilizing said body about a given axis, means responsive to radiant energy for rendering said stabilizing means either operative or inoperative to stabilize said body, and means carried by said body and automatically operative to restore said stabilizing means to an operative condition to stabilize said body after said stabilizing means, in response to radiant energy, has been rendered inoperative to stabilize said body.

5. The combination with a dirigible body, of stabilizing means carried thereby and automatically operative to stabilize said body about a predetermined axis, means responsive to radiant energy for controlling the potentiality of said stabilizing means to stabilize said body, and automatically operative means carried by said body and including an element automatically movable with respect to said body at a rate dependent upon the rate of movement of said body for automatically controlling the potentiality of said stabilizing means.

6. The combination with a dirigible body, of means carried thereby for propelling the same, stabilizing means carried by said body and automatically operative to stabilize said body about a predetermined axis, means responsive to radiant energy for controlling the potentiality of said stabilizing means to stabilize said body, and means controlled by said propelling means and also by said means responsive to radiant energy, and operative automatically to control the potentiality of said stabilizing means.

7. The combination with a dirigible body, of means carried thereby for automatically stabilizing the same about a predetermined axis, means responsive to radiant energy and operative to vary the action of said stabilizing means and to rotate said body about said axis, and means carried by said body and controlled by said second mentioned means for varying the potentiality of said stabilizing means after the potentiality of said stabilizing means has been varied by the action of an impulse of radiant energy, and after said impulse has ceased.

8. The combination with a dirigible body, of means carried thereby for propelling the same, stabilizing means carried by said body and automatically operative to stabilize said

body about a predetermined axis, means responsive to radiant energy for controlling the potentiality of said stabilizing means to stabilize said body, and means arranged to operate after a predetermined time for automatically varying the potentiality of said stabilizing means to control said body.

9. The combination with a dirigible body, of means carried thereby for propelling the same, stabilizing means carried by said body and automatically operative to stabilize said body about a predetermined axis, means responsive to radiant energy for controlling the potentiality of said stabilizing means to stabilize said body, and means including an element reciprocable at a definite rate for automatically varying the potentiality of said stabilizing means to control said body.

10. The combination with a dirigible body, of means carried thereby for propelling the same, stabilizing means carried by said body and automatically operative to stabilize said body about a predetermined axis, means responsive to radiant energy for controlling the potentiality of said stabilizing means to stabilize said body, means including a cam controlled element for varying the potentiality of said stabilizing means, and means for rotating said cam at a rate proportioned to the rate of movement of said movable body.

11. The combination with a dirigible body, of means carried thereby for propelling the same, stabilizing means carried by said body and automatically operative to maintain the body on a given course, means responsive to radiant energy for modifying the course of the body for a predetermined extent of travel of the body, and means for causing the body to assume a course parallel to the original course.

12. The combination with a dirigible body, of means carried thereby for propelling the same, a gyroscope carried by said body and automatically operative to maintain the body on a given course, means responsive to radiant energy for modifying the course of the body for a predetermined extent of travel of the body, and means for causing the body to assume a course parallel to the original course.

13. The combination with a self-propelled dirigible body, of a steering device therefor, a gyroscope connected to the steering device so as to normally retain the course of the body, a radio receiving mechanism responsive to radiant energy for disconnecting the gyroscope from the steering device, and means operative after the body has been propelled to a predetermined extent with the gyroscope disconnected to connect the gyroscope to the steering device.

14. A system for controlling the operation of vessels at a distance by radiant energy, including in combination a vessel to be propelled having a gyroscope to impart there-

- to a predetermined or definite direction of movement controlled means for transmitting radiant energy from a distance, means responsive to such radiant energy from the 5 distance to release the vessel from the action of said gyroscope, and means operative only after the vessel is moved a predetermined distance while released from the action of the gyroscope to restore the vessel to control 10 by the gyroscope.
15. A system for controlling the operation of vessels at a distance by radiant energy, including in combination a vessel to be propelled having a gyroscope to impart thereto 15 a predetermined or definite direction of movement, controlled means for transmitting radiant energy from a distance, means responsive to such radiant energy from a distance to release the vessel from the action 20 of said gyroscope, and to direct the bodily movement thereof, and means operative only after the vessel is moved a predetermined distance while released from the action of the gyroscope to restore the vessel to control 25 by the gyroscope.
16. The combination with a movable body, of means to stabilize said body with respect to a given axis, means responsive to radiant energy, to modify the control of said body 30 by said stabilizing means and to rotate said body selectively in either direction about said axis, and means operative upon a predetermined extent of movement in the selected direction to rotate said body in the opposite direction about said axis a substantially equal amount.
17. The combination with a movable body, of means automatically operative to stabilize said body with respect to a given axis, 40 and fluid actuated means responsive to radiant energy to modify the control of said body by said stabilizing means and to rotate said body selectively in either direction about said axis, and means operative upon a predetermined extent of movement in the selected direction to rotate said body in the opposite direction about said axis a substantially equal amount.
18. The combination with a movable body, 45 of means including a gyroscope automatically operative to stabilize said body with respect to a given axis, means responsive to radiant energy to modify the control of said body by said stabilizing means and to rotate said body selectively in either direction about said axis, and means operative upon a predetermined extent of movement in the selected direction to rotate said body in the opposite direction about said axis a substantially equal amount.
19. The combination with a movable body, of means automatically operative to stabilize said body with respect to a given axis, means to modify the automatic operation of said stabilizing means and to rotate said 55 body selectively in either direction about said axis, and means operative upon a predetermined extent of movement in the selected direction to rotate said body in the opposite direction about said axis a substantially equal amount.
20. The combination with a movable body, of means automatically operative to stabilize said body with respect to a given axis, means to vary the automatic operation of said stabilizing means and to rotate said body selectively in either direction about said axis, and means operative upon a predetermined extent of movement in the selected direction to rotate said body, in the 60 opposite direction about said axis a substantially equal amount.
21. The combination with a movable body, of means automatically operative to stabilize said body with respect to a given axis, 65 means to modify the automatic action of said stabilizing means and to rotate said body selectively through any desired angle about said axis, and means operative upon a predetermined extent of movement of said body after rotation through said angle to rotate said body in the opposite direction through substantially an equal angle about said axis.

Signed at New York, in the county of New York and State of New York, this 14th day of April, A. D. 1920.

ALBERT D. TRENOR.
